HAND BAG

Herman I. Kenler, New York, N. Y.

Application December 13, 1934, Serial No. 757,270

5 Claims. (Cl. 150—29)

This invention relates to portable receptacles, and has particular reference to devices such as framed handbags.

One object of the invention is to provide a device of the character described having a slide fastener in improved association with a frame element to produce a neat, attractive inexpensive handbag, which shall be easier to fabricate, and which shall permit varying constructions and 10 designs to be employed in the structure of the device.

Another object of the invention is the provision of a device of the nature set forth having improved means for mounting a slide fastener; improved means for maintaining a flexible handbag and slide fastener in taut operative conditions; improved means whereby the normal capacity of the handbag may be increased; improved means to prevent the slide fastener from being 20 transversely distorted and so as to be maintained uniform when subjected to external lateral pressure on the bag; improved means whereby irregularities in the clamped channel frame elements will not affect the closing of the handbag as in conventional handbags in which the inner flanges must be perfectly plane, and hence this invention permits bodies of varying sizes to be clamped 25 in the channel members.

Another object of the invention is to furnish 30 a device having few and simple parts and which is inexpensive to manufacture, durable, reliable and efficient in use; and also an improved method of making the device.

Other objects and advantages of the invention 35 will become apparent as the specification proceeds.

With the aforesaid objects in view, the invention consists in the novel combinations and arrangements of parts hereinafter described in their 40 preferred embodiments, pointed out in the subjoined claims, and illustrated in the annexed drawing, wherein like parts are designated by the same reference characters throughout the several views.

45 In the drawing:

Figure 1 is a view in front elevation showing a device embodying the invention.

Fig. 2 is a top plan view thereof.

50 Figs. 3 and 4 are enlarged fragmentary section-al views taken on the respective lines 3—3 and 4—4 of Fig. 1.

Fig. 5 is an enlarged horizontal sectional view taken through one of the channel members at the portion intermediate the ends thereof.

55 The advantages of the invention as here out-

lined are best realized when all of its features and instrumentalities are combined in one and the same structure, but, useful devices may be produced embodying less than the whole.

It will be obvious to those skilled in the art to which the invention appertains, that the same may be incorporated in several different constructions. The accompanying drawing, therefore, is submitted merely as showing the preferred 5 exemplification of the invention.

Referring in detail to the drawing, 10 denotes a device embodying the invention. The same may include a bag 11 of any suitable pliable or flexible material, preferably leather, and having a pair of side walls 12, 13, which may be exact duplicates 15 of each other, these walls being continuously interconnected to provide a pocket 14, accessible through an opening extending along the top and partially down the ends of the bag.

Associated with the bag 11 is a relatively rigid 20 frame which may include one or more frame elements such as the channel members 15, 16, each of which may be a duplicate of the other. Desirably the channel members are movable toward and away from each other to close and open the 25 bag, and they may be pivotally interconnected as at 17. The channel members may be of regular or inverted type, but the latter best exemplifies

the advantages of the invention; and the channels may be of any suitable shape, it being sufficient 30 that sharp corners transverse of the channels be avoided. In the channels, the marginal portions 18 of the bag walls may be clamped, these marginal portions extending longitudinally of the channel elements, and the bag walls extending 35 over downward along the outer flanges 19 of the channels. As thus far described, the construction of the bag and channels is conventional.

Extending continuously along the channel members is any well known slide fastener 20, 40 which may include a pair of series of releasably engaging hooks 21, each series being mounted on its individual one of the stringers 22, 23. The slide fastener may extend to the region of the frame pivots 17, and may be finished there- 45 at in any suitable manner as by outward projecting end portions of the stringers at 24, interconnected at each end of the bag by a tab 25, or the like, whereby the bag can be fully opened in the open position of the slide fastener. 50 The latter may have a usual slide 26 that is at one end of the bag in open position, and at the opposite end of the bag in closed position.

According to my invention, the slide fastener 20 is mounted to lie in the region between the 55

channel members, so as to constitute a continuous longitudinal bridge therebetween, with the channel members affording lateral support for the slide fastener to prevent undue strain or distortion thereof or of the stringers. The invention also provides for the direct clamped engagement of the stringers in the channel members. Since the stringers are preferably made of a textile fabric, or other thin and rather hard or incompressible pliable material, they will slip out of the channel members when subjected to strain. If the channel members be clamped sufficiently tight to securely hold the stringers, the relatively soft handbag fabric, such as leather, will be unduly compressed and weakened, and sometimes even cut.

I have found that this defect can be remedied by securing as by stitching at 27, strips of a relatively compressible frictional material, such as leather, longitudinally along the margins of the stringers, these strips preferably facing the inner flanges 29 of the channel members and having at least partial contact with the marginal portions of the bag walls. These strips 28 are wholly contained in the channels, near the lower parts thereof, so as to be concealed in the channel members.

Hence it will be seen that I have provided means whereby relatively soft compressible and relatively hard, thin incompressible elements may be secured in the channel members without damage to the former, this principle being of general application, but having especial advantage in connection with a slide fastener 35 stringer which must of necessity be both thin and very strong, so that the hooks can be reliably anchored thereto, without producing tears in the stringer and without rendering the slide fastener bulky. The invention permits a handbag to be fabricated with the stringer being separate of the bag wall, in other words unconnected thereto, so that the bag wall and stringer can be separately inserted into the channel for the clamping operation. Hence a rapid 40 fabrication is obtained, wrinkling and drawing as between the bag wall and the strong non stretching stringer avoided, and the fold at 30 in the bag wall may be made neat and even, without interference by the stringer, which is thereafter inserted into the channel, prior to 45 the clamping. It will be appreciated that the stringers 22, 23 are representative of one or more flaps, and where two of them are provided, they may be considered as flexible marginal portions 50 along the stiff edges of the bag opening, and releasably secured together by any suitable means such as the hooks 21.

The slide fastener stringers 22, 23 may overlie the inner flanges 29 of the channel members, and in the closed position of the slide fastener, the channel members are spaced from each other to a greater or less degree depending on the width of the exposed portions of the stringers. Thus the normal capacity of the bag is materially increased. The channel members, in their flanking positions relative to the slide fastener, support and maintain the same uniform.

A particular advantage which results from this invention is that the channel members may be irregular in width or shape, or may become so upon clamping bodies of varying thicknesses therein, and nevertheless the closing of the bag may be accurately accomplished. In other words, it is unnecessary that the inner flanges shall lie 75 in uniformly parallel planes throughout. Thus,

if the handbag walls be provided with a pleat 31 or the like, for added bag capacity, or for increased strength or for decorative purposes, such pleat may be continued to a margin of the bag for ease in manufacture, and may be directly 5 clamped in the channels.

For more specifically illustrating the advantage mentioned, I show the pleat structure 31, as embodied in a bag wall consisting of two sections having spaced marginal portions 32 10 folded away from each other and lying in the same plane, a backing strip of material 33 being stitched at 34 to the portions 32. In Fig. 1, the strip 33 is observed as forming the interior or base of the pleat, and in Fig. 5, this 15 strip is near the outer flange 19, because the bag wall is folded over said flange. By this arrangement the stitching does not appear on the outside of the bag, and the pleat is held against opening up along the bag. The pleat 20 structure may of course be sewed into the bottom 35 of the bag in any suitable manner. The channel member thus receives three thicknesses 25 of bag wall material, so that when the channel is clamped a bulge B occurs therein at the 30 pleat structure. In a conventional type of bag, this would cause great difficulty, because if the bulge were inward, the channel frames would not meet uniformly for continuously tightly closing the handbag. If the bulge were outward, 35 the bag would show the bulge on the outside and the bag material would wear rapidly, and lose its finish at the bulge. By this invention, the bulge may extend inward, the spacing between the channels affording ample clearance for reception of the bulge or other irregularity.

If a plate 36 were secured in the channel member to hold an ornament, or the like, the bulge B will still further increase.

To maintain the channel members 15, 16 in 40 spaced relation, so as to prevent them from being pressed toward each other as where the bag is carried under the arm, with resulting deformation of the slide fastener and continued wrinkling of the stringers, I may provide suitable spacing 45 means on the frame under the slide fastener. Preferably the plates 36, which may be secured to the inner flanges 29 of the channels on the inside or outside thereof may have resilient portions 37 bent over the inner flanges and spaced 50 inward thereof, so that when the slide fastener is closed, the different elements 37 resiliently abut each other to tend to move the channels apart and to transversely tension the slide fastener.

It will be appreciated that various changes and 55 modifications may be made in the device as shown in the drawing, and that the same is submitted in an illustrative and not in a limiting sense, the scope of the invention being defined in the following claims.

I claim:

1. A handbag including a channel member, a bag having a opening, a slide fastener for said opening, the slide fastener having a hook bearing stringer of a relatively incompressible thin material, said stringer and a portion of the bag wall being clamped in said channel member and being otherwise separate of each other, a strip of a body 65 providing compressible flexible material connected to the stringer therealong, and the body forming strip being positioned wholly within the channel member, so as to be concealed therein and to prevent the stringer from slipping out of the channel member.

2. A handbag having separate compressible and 70

- relatively incompressible pliable fabric elements, a channel member receiving marginal portions of said elements, said elements being otherwise unconnected with each other, a strip of a compressible pliable fabric secured to the margin of the incompressible element, said strip being confined wholly within the channel member, and the latter being clamped, whereby the different elements can be secured in the channel member without exerting a clamping pressure sufficient to cut the compressible fabric element. 5
3. A handbag having a frame including a plurality of inverted channel members movable toward and away from each other, a bag having walls clamped in the channel members and overlying the outer flanges of the latter, a slide fastener extending between and having stringers clamped in the channel members, the stringers overlying the inner flanges of the channel members and the latter being spaced from each other in the closed position of the slide fastener, and resilient means mounted on the frame under the slide fastener and tending to actuate the channel members apart to transversely tension the slide fastener. 10
4. A handbag having a plurality of inverted channel members, a bag having an opening, flap-like pliable members for the opening, the pliable members overlying the inner flanges of the channel members and extending into the latter, means for releasably interconnecting the pliable members to close the bag, the bag having an opening and side walls, at least one of the side walls hav- 15
- ing a thickened reinforcement portion transverse to a channel member, the side walls having marginal portions overlying the outer flanges of the channel members and extending thereto, and the pliable members and the said marginal portions including the said reinforcement portion being clamped in their corresponding channel members, with said reinforcement portion extending downward along and adapted to afford a substantial support to its side wall to prevent the side wall from being stretched by the stress caused by the weight or bulk of articles normally carried in the bag and to transmit a substantial portion of such stress direct to its channel member. 20
5. A handbag including a one piece channel member having a single channel space, a bag having a wall and an opening extending therewith, a pliable marginal flap like member for said wall, a strip element continuously secured to the pliable member along a margin thereof, the marginal portion of the wall being received in the channel of the channel member, the strip element being wholly received in said channel member with the marginal portion of said wall, and the channel member being clamped to mount as a unit the said marginal portion and the strip element in said channel member with the strip element concealed in the channel member, and the said marginal portion and the pliable member lying substantially wholly parallel to the flanges of the channel member. 25 30
